FOLDABLE CLOSURE

William A. Shearer, New Castle, Ind.

Application September 25, 1943, Serial No. 503,753

13 Claims. (Cl. 160—84)

This invention relates to foldable closures of the general type illustrated in prior Patents No. 2,220,939 dated November 12, 1940, and No. 2,321,507 dated June 8, 1943.

In said patents there is disclosed an articulated framework including a pair of superposed lazy-tongs structures with one or more parallel series of hinge plates suitably connected together and to said structures, same being suitably covered by fabric or like material, the resulting foldable closure being capable of suspension from an overhead track or otherwise suitably supported as recited in said patents.

The foldable closure of the present invention is broadly of similar character, to-wit, it collapses and extends to expose or close the opening, respectively, it may be track supported, it may be permanently or semi-permanently attached to a wall of the opening and it may be fabric or like covered upon one or both sides as desired. So far as the operator is concerned it functions like the patented structures.

The chief object of the present invention, therefore, is to retain all the aforesaid structural advantages of said patented structures and at the same time accomplish such results with a minimum number of parts and this by the elimination of the force determining elements, to-wit, the lazy-tongs and this by including in the hinged plates such force determining factors.

The chief feature of the present invention, therefore, resides in the utilization of a dual, lazy-tongs type, articulated, hinged plate single unit in lieu of a lazy-tongs and a single series of hinged plates.

Other objects and features of the invention will be set forth more fully hereinafter.

The full nature of the invention will be understood from the accompanying drawings and the following description and claims:

In the drawings Fig. 1 is a horizontal sectional view of the foldable closure in collapsed position and a side wall of the opening.

Fig. 2 is a similar view of a small portion of such closure upon a larger scale (substantially full scale) with the parts shown in the extended relationship.

Fig. 3 is a side elevation of the uppermost articulated structure and a supporting track etc., parts being broken out.

Fig. 4 is a top plan view of a left half hinge plate.

Fig. 4A is an elevational view thereof.

Fig. 5 is a top plan view of a right, full hinge plate.

Fig. 6 is an elevational view of said plate shown in Fig. 5.

Fig. 7 is a top plan view of a left, full hinge plate.

Fig. 8 is an elevational view of said plate shown in Fig. 7.

Fig. 9 is a top plan view of a right, half hinge plate.

Fig. 10 is a top plan view of a hinge connector.

Fig. 11 is a side elevation thereof.

Figs. 12, 13 and 14 are perspective views of the two intersecting hinge plates shown in Figs. 5 to 8 and in different assembling and disassembling positions.

In Fig. 1, 10 indicates one side wall of an opening, in Fig. 2, 11 indicates the opposite side wall thereof and in Fig. 3, 12 indicates the top of same and incorporated therein is the track 13 which is substantially similar to those illustrated in said patents.

A post 14 is semi-permanently attached to wall 10 and rigid therewith is the channel-sectioned member 15. Fabrics 16 and 17 have adjacent ends lapped and anchored between post 14 and member 15 and the latter is concealed thereby. Rigid with the interior of channel 15 is, see also Figs. 10 and 11, a hinge connector 18 having a plurality of spaced cylindrical portions 19 longitudinally aligned and constituting a support for a pintle 20. The aforesaid constitutes the anchored end of the foldable closure.

Referring to Fig. 2, wall 11 has semi-permanently secured thereto post 21 provided with groove 22. The other end of the foldable closure includes a tubular, movable post 23 covered by the other side edges of fabrics 16 and 17 and lapped and retained by the bumper structure including member 24 which mounts and from which projects cushion 25 for seating in recess 22 when the closure is extended.

Post 23, see Fig. 3, near its upper end pivotally supports at 26 a plate 27 that projects upwardly into the downwardly opening slot in track 13. Said plate carries axles 28 upon the ends of which 45 are mounted wheels 29 that ride the lower inside flanges of the track. A cushioning structure may be provided as set forth in the later patent. Also intermediate track engaging guide and supports, indicated at 30, may be provided. Note 50 also that secured to the tubular post, opposite member 24, is a corresponding hinge connector 18 with pintle support portions 19 for a pintle 20.

To the left hand hinge connector is secured a right hand and a left hand half hinge plate, see 55 Figs. 4 and 9 respectively. Likewise two comple-

mentary half hinge plates are pivotally secured to the right hand hinge connector. Therebetween are secured the right and left hand hinge plates as shown in Figs. 1 and 3, which plates are illustrated more fully in Figs. 5 to 8 and 12 to 14 inclusive.

Fig. 1 illustrates the collapsed position of the several hingedly connected full and half plates. Fig. 2 illustrates the extended position of certain of the same. Each full plate is apertured at 31, see Figs. 6 and 8, and each half plate similarly. These apertures provide for connectors to be applied to the several plates and anchor the fabric sheets 16 and 17 thereto so that same follow the articulated hinging in its collapse and extension is illustrated in Figs. 1 and 2. Such fabric connection is illustrated in the earlier patent, although others may be utilized.

It is to be understood herein that, at least one such hinging arrangement is utilized and this is at the top of the closure. If a second be utilized, and it usually is, same lies near the bottom of the closure. If desired, any number of intermediate series of hinging arrangements may be utilized therebetween.

Each hinge series is similarly mounted on the movable post 23 and stationary channel 15 as illustrated and by hinge connectors secured thereto. These superposed series of hinge plates can be connected vertically through elongated pintles, same mounting suitable washer like stops or retainers as shown in the later patent. This prevents progressive sag, although if desired, suitable center pintles may be extended upwardly as at 30, see Fig. 3, and mount track bearing rollers. Preferably the number thereof is not large, since the accumulation when collapsed might prevent complete collapse of the closure as shown in Figs. 1 and 3.

It will be noted that so far no mention of lazy-tongs links has been made relative to the present invention. This is an intentional omission and simplification for the intersecting hinge plates have the dual function of serving as a lazy tongs and a successively hinged plate series.

While it is possible to utilize two hinged series of plates of relatively narrow depth and have one on one side and the other on the other side of what might be termed the projected lazy tongs outline, such will neither have the stability of a lazy tongs nor can same serve as a top edge support for the covers at both sides of the plates etc. nor compel proper folding at each fold, as with the patented structures and that herein disclosed.

The intersecting character of the hinge plates accordingly permits of this simplification and permits two hinge plates herein to simultaneously serve the same purposes as two crossed links and a hinge plate without track guidance of all center pintles.

The invention also contemplates the biasing of the midportion of the several plates, same permitting the plates, with included fabric covering, to completely collapse without pinching or binding and such biased portions cooperate when extended to abut and limit extended movement, leaving the fabric when extended with regular folds therein.

Reference will now be had to Figs. 4 and 9 wherein the two half hinges are illustrated in plan and Fig. 3 which illustrates the same in elevation. Herein 34 indicates the left half hinge plate with angular offset portion 35 and cylindrical portions 33 and 36 at opposite side edges.

In like manner the right hand half plate 38 includes biased portion 39 and opposite side edges 40 include the cylindrical pintle bearing portions 37 and 40 respectively. Two of these plates are interfitted together and connected to the hinge connector 18 at 19 by means of pintle 20.

Reference will now be had to Figs. 5 and 6 wherein the socalled right hand plate is illustrated. Each plate includes a pair of wings or leaves 41 which extend parallel to each other and are offset end-to-end being connected by a central biased portion 42, the angularity of same to the adjacent leaf being the same as in the corresponding half hinge. The side edges of the leaves include cylindrical pintle bearing portions 43. Note, however, same at opposite sides of the plate are offset or staggered.

The central biased portion 42 has an elongated longitudinally directed opening 44 therein and projecting laterally thereof across the biased portion 42 and into the leaf portion 41 are the oppositely directed generally triangular like extensions 45. Same may be extended further as indicated at 45A, see dotted lines as hereinafter pointed out. Herein biased portion 42 at each end includes a pair of longitudinally aligned, oppositely directed, semi-cylindrical pintle bearing portions 46 whereby a pintle may be self sustained in this plate without regard to any other plate.

Reference will now be had to Figs. 7 and 8 wherein is illustrated what may be termed the so-called left hand plate. Same includes parallel but similarly offset leaves or wings 50 joined by a central biased portion 51 including at opposite ends inwardly directed notches 52, leaving therebetween a portion 53 having a length slightly less than the length of opening 44 in the other plate. This intermediate portion between the roots of said notches includes a plurality of parallel slits 54. This provides a plurality of pairs of longitudinally aligned semi-cylindrical pintle bearing portions 55, adjacent pairs of bearings being oppositely directed. Note in Fig. 8 the intermediate pair of bearings are integral and continuations of each other.

Whenever extensions 45A in the right hand plate are included the entrance to notches 52 need not be rounded as at 56 but may be square as shown dotted at 56A. The opposite side edges of the plate include longitudinally aligned but spaced elongated cylindrical pintle bearing portions 57.

Figs. 12 to 14 illustrate how a pair of these different plates are progressively associated together or disconnected from each other. When fully associated, the plates intersect and a single pintle 58 simultaneously connects them together at their midpoints and seats in bearings 53 and 46. Pintles 59 connect the adjacent side edges of adjacent plates on one side of the closure and similarly pintles 60 connect the adjacent side edges of adjacent plates on the opposite side of the closure.

While the invention has been illustrated and described in great detail in the drawings and foregoing description, the same is to be considered as illustrative and not restrictive in character.

The several modifications described herein, as well as others which will readily suggest themselves to persons skilled in this art, all are considered to be within the broad scope of the invention, reference being had to the appended claims.

The invention claimed is:

1. A foldable closure including a sequentially connected series of full length hinge plates, arranged in pairs, the plates of each having a common pivotal connection midway between the ends, the adjacent ends of adjacent plates having a pivotal connection, for dual plate construction whereby the plates serve as a lazy-tongs.

2. A foldable closure as defined by claim 1 wherein each plate includes a covering anchorage portion, and a covering for each side of the closure.

3. A foldable closure as defined by claim 1 wherein a pair of half length plates have a common pivotal connection at their adjacent ends and have their other ends pivotally connected to the adjacent ends of the end plates of the sequential series of full length plates.

4. A foldable closure as defined by claim 1 wherein a pair of half length plates have a common pivotal connection at their adjacent ends and have their other ends pivotally connected to the adjacent ends of the end plates of the sequential series of full length plates, each half plate having a biased portion adjacent the common pivoted end and including said end.

5. A foldable closure as defined by claim 1 wherein each plate includes an intermediate biased portion, said portions permitting alignment when collapsed and limiting extension when extended.

6. A foldable closure as defined by claim 1 wherein each plate includes an intermediate biased portion, said portions permitting alignment when collapsed and limiting extension when extended, a pair of half length plates having a common pivotal connection at their adjacent ends and having their other ends pivotally connected to the adjacent ends of the end plates of the sequential series of full length plates.

7. A foldable closure as defined by claim 1 wherein each plate includes an intermediate biased portion, said portions permitting alignment when collapsed and limiting extension when extended, a pair of half length plates having a common pivotal connection at their adjacent ends and having their other ends pivotally connected to the adjacent ends of the end plates of the sequential series of full length plates, each half plate having a biased portion adjacent the common pivoted end and including said end.

8. A foldable closure as defined by claim 1 wherein each pair of plates has an intersecting association, one having a central opening for partially passing part of and pivoting the other plate into position for common pivotal connection.

9. A foldable closure as defined by claim 1 wherein each pair of plates has an intersecting association, one having a central opening for partially passing part of and pivoting the other plate into position for common pivotal connection, each plate including a covering anchorage portion, and a covering for each side of the closure.

10. A foldable closure as defined by claim 1 wherein each pair of plates has an intersecting association, one having a central opening for partially passing part of and pivoting the other plate into position for common pivotal connection, a pair of half length plates having a common pivotal connection at their adjacent ends and having their other ends pivotally connected to the adjacent ends of the end plates of the sequential series of full length plates.

11. A foldable closure as defined by claim 1 wherein each pair of plates has an intersecting association, one having a central opening for partially passing part of and pivoting the other plate into position for common pivotal connection, and each plate includes an intermediate biased portion, said portions permitting alignment when collapsed and limiting extension when extended.

12. A foldable closure as defined by claim 1 wherein each pair of plates has an intersecting association, one having a central opening for partially passing part of and pivoting the other plate into position for common pivotal connection, a pair of half length plates having a common pivotal connection at their adjacent ends and having their other ends pivotally connected to the adjacent ends of the end plates of the sequential series of full length plates, each half plate having a biased portion adjacent the common pivoted end and including said end.

13. A foldable closure as defined by claim 1 wherein each pair of plates has an intersecting association, one having a central opening for partially passing part of and pivoting the other plate into position for common pivotal connection, and each plate includes an intermediate biased portion, said portions permitting alignment when collapsed and limiting extension when extended.

14. A foldable closure as defined by claim 1 wherein each pair of plates has an intersecting association, one having a central opening for partially passing part of and pivoting the other plate into position for common pivotal connection, and each plate includes an intermediate biased portion, said portions permitting alignment when collapsed and limiting extension when extended, a pair of half length plates having a common pivotal connection at their adjacent ends and having their other ends pivotally connected to the adjacent ends of the end plates of the sequential series of full length plates, each half plate having a biased portion adjacent the common pivoted end and including said end.
